UNITED STATES PATENT OFFICE.

JULIUS KAUFFMANN, OF BERLIN, GERMANY.

PROCESS FOR RENOVATING COTTON-WASTE.

1,026,267.

Specification of Letters Patent.

Patented May 14, 1912.

Application filed March 1, 1910. Serial No. 546,759.

To all whom it may concern:

Be it known that I, JULIUS KAUFFMANN, a subject of the Emperor of Germany, and resident of Berlin, Germany, have invented 5 a certain new and useful Improvement in Processes for Renovating Cotton-Waste, of which the following is a specification.

This invention relates to a process of extracting dirt, oil, etc., from dirty cotton or 10 other waste, by washing the same for the purpose of dissolving out the oil by means of a solvent evaporating the solvent and drying the waste so that it may be used again.

15 The feature of the invention consists in this that in all three stages of the process air under pressure alone is employed for agitating and loosening the waste.

Apparatus for performing this process is 20 shown diagrammatically by way of example in the accompanying drawing.

Referring to the drawing, 1 is a flat vessel in which is arranged on supporting cheeks 3 a perforated flat receptacle 2. This receptacle 25 serves to hold the waste to be purified, which waste is introduced through manhole doors on the upper side 4 of the vessel.

The pipe connection 9 serves for the introduction of the purifying agent, (carbon tetrachlorid). The pipe 11 controlled by the 30 valve 10 serves to connect the vessel either with the pipe 13 leading to the chimney and controlled by valve or cock 12 or with a pipe 15 controlled by valve or cock 14 and leading

35 to a separating chamber. The vessel is heated by means of a coil 16 supplied with steam which does not admix with the solvent.

17 is a pipe controlled by a valve 18 for draining off that portion of the solvent 40 which is not volatilized in the distillation process and the oil, etc., separated from the waste.

19 is a dome provided with a branch 20 leading to the cooler 23 and through which 45 the volatilized solvent passes off.

The finely perforated pipe 21 arranged at the bottom of the receptacle along the side thereof and connected to a high pressure fan by a branch 22 serves to carry air through 50 the waste while the same is being washed by the solvent at the commencement of the distillation or while the waste is being dried.

In addition to the ordinary fittings a gage glass is provided on the vessel 1 for the

purpose of observation of the level of the 55 liquid therein.

The waste is purified in the following manner: Firstly the waste is introduced through the manhole doors 5 into the receptacle 2; after the valves 12 and 18 are closed 60 the solvent is run in up to the necessary level and air is driven from a high pressure fan through the tube 21 and through the waste in the receptacle 2 in such manner that all parts of the waste are thoroughly agitated 65 and washed with the solvent. The separated oil and the superfluous portion of the solvent are removed through pipe 11, valves 10 and 14 to the separating chamber. Distillation of the solvent is then effected by heating the 70 coil 16; the valves 10, 12, 14 and 18 being kept closed. This operation is continued until the level of the liquid in the vessel 1 falls below the bottom of the receptacle 2. Valve 18 is then opened in order to lead off 75 the non-volatile parts of the solvent and the separated oil from the vessel. The distillation may thereupon be repeated by running in fresh solvent through the pipe 9 and heating by means of the heating coil 16. After 80 purification, drying is effected by passing air from a high pressure fan through the receptacle 2 by way of the perforated tube 21. The valve 15 is closed and valve 12 is opened so that the air together with the dust-like 85 impurities still contained in the waste are led off through the pipe connection 13 to the chimney.

Having described my invention what I claim and desire to secure by Letters Patent 90 of the United States is:—

The herein described process of renovating solid cotton waste, consisting in washing the same with a volatile solvent liquid and blowing compressed air through the liquid to agitate the waste, evaporating the solvent by the action of heat and simultaneously blowing compressed air through the waste to prevent packing, and finally drying the waste and blowing off dust by the action of compressed air.

In testimony whereof I have signed my name to this specification in the presence of two subscribing witnesses.

JULIUS KAUFFMANN.
